UNITED STATES PATENT OFFICE

1,926,674

BASKET BALL BACKSTOP

Elmer J. Gross, Chicago, Ill., assignor to Chicago Gymnasium Equipment Company, Chicago, Ill., a corporation of Illinois

Application March 19, 1931. Serial No. 523,661

3 Claims. (Cl. 273—1)

This invention relates to the supporting structure for basket ball boards, and is of that class for use in gymnasiums, wherein it is desirable to suspend the board and frame structure therefrom from an overhead support, and to provide for swinging the supporting frame and board from a vertical operating position to an upper horizontal position where the board may be out of the way and out of the line of vision in case the gymnasium is to be used for auditorium purposes.

The objects of the invention are to provide a construction of this class which is of neat appearance and simple design and free from likelihood of breakage, particularly when lowering the structure from horizontal to vertical position. In case the hoisting line is released, or breaks, provision is made for checking and cushioning the downward swing of the board and its support. A further purpose of the invention is to provide telescoping inclined rear braces for the board and its supporting frame, arranged to provide a pneumatic cushioning means for easing the downward motion of the frame from horizontal to vertical positions.

The objects of the invention are accomplished by means of a construction illustrated by the drawings, in which:

Figure 1 is a side view of the improved basket ball backstop construction.

Fig. 2 is a front view of the same with the board partly broken away.

Fig. 3 is an enlarged sectional detail in front elevation to show a bearing construction of telescoping diagonal rear braces of the backstop.

Basket ball backstops of the class to which this invention relates comprise the three principal elements of the board, hanger frame supports by means of which the board is suspended from the ceiling beams or other frame supporting means, and inclined bracing means extending rearwardly and upwardly from the bottom of the board hanger frame to the ceiling.

The present improvement relates particularly to the construction of these inclined braces, which, in the present case, consist of telescoping members to provide for the required extension of such inclined braces when the construction is swung upwardly to horizontal position parallel with the ceiling; and to provide by these extensible telescoping members a pneumatic cushioning arrangement for the purpose of safety and to allow an easy action when lowering the backstop to its vertical position. The pneumatic cushioning means further serves to relieve the

operator of some of the apparent weight of the construction when it is moving downwardly, as the air is released from the telescoping means through restricted air outlets therein.

Referring to the drawings, a basket ball board 1 is shown rigidly secured to a frame consisting mainly of a pair of hangers 2 depending from hinged connections 3, with fixed supports 4 at the upper ends of hangers 2. The board 1 is secured to pads 5 at its corners, which are integral with collars 6 surrounding and fixed to the hangers 2. The hangers 2 are preferably connected together, as shown in Fig. 2 by a horizontal brace 7 and diagonal braces 8. For the purpose of raising and lowering the structure by swinging it around the hinges 3, a cable 9 is attached to the horizontal brace 7 and leads upwardly therefrom to an overhead pulley, and from there to a hoisting winch, not shown.

For the purpose of bracing the board and its supporting structure when in vertical position, telescoping elements 10 extend rearwardly and upwardly from the lower ends of the hangers 2 to hinges 11 on the fixed supports 12. The supports 12, like the supports 4, may be made in various forms for attachment to the ceiling beams, joists or struts, or overhead pipes. As shown in the drawings, these members are arranged for being clamped to fixed horizontal pipes 13. The outer tube 14 of each telescoping member 10 is connected at its upper end to the hinge 11, and the inner tube or bar 15, which is slidable within the tube 14, is pivotally connected at its lower end to a fitting 16 secured to one of the board supporting members 2.

The telescoping members 14 and 15 are of such internal and external diameters as to provide clearance between the same for free relative movement, but the member 14 carries a bearing 17 at its lower end, which more exactly fits the inner tube 15. This bearing member is split at its upper end as shown at 18, in Fig. 3, and is provided with ears through which pass the bolts 20, by means of which the bearing is securely clamped to the tube 14. It is also preferably provided with felts 19 for carrying a lubricant and making a fairly airtight seal between the bearing and the tube 15. When the construction is swung downwardly from its horizontal to its vertical position, the tube 15 slides upwardly in the tube 14, and compresses the air therein. The lower end of tube 15 is closed by the socket member 20, by means of which the tube is pivotally attached to the fitting 16. The air which is compressed in tube 14 is released at the desired

rate through a perforation 21 at the upper end of this tube.

The bearing members 17 also have ears 22 for attachment to the diagonal braces 23 extending 5 from the bearings to the upper ends of the tubes 14, to which they are connected by fittings 23.

For the purpose of latching the tubes 14 and 15 together in the frame bracing position, the tube 15 is perforated at 24 to receive a locking bolt 25, 10 slideable within a boss 26 formed on the bearing 17 and carrying a spring 27 for urging the bolt 25 inwardly. Attached to the heads of each of the bolts 25 is a perforated bent metal element 28, by means of which the bolts are connected together 15 by a chain 29. Depending from the chain 29 is a pull chain 30, which when pulled downwardly serves to withdraw the locking bolts from the apertures 24 and permit the structure to be swung upwardly to its horizontal position.

20 Thus, in the operation of the construction above described, if it is desired to raise it from the vertical to the horizontal position where it will be out of the way, chain 30 is pulled downwardly and then the construction may be swung upwardly by 25 means of the cable 9. In lowering the backstop from a position along the ceiling to the vertical position, as shown in Figs. 1 and 2, the tube 15, which is pivotally attached to the upright members 2, slides within the tube 14, compressing the 30 air therein and thus cushioning the descent of the backstop construction. The rate of descent is determined by the leakage of air through the perforations 21. This air cushioning arrangement prevents the jar which would occur if the hoisting 35 cable is suddenly released, and avoids the danger of breakage through such action.

Although but one specific embodiment of this invention has been herein shown and described, it will be understood that certain details of the 40 construction shown may be altered or omitted without departing from the spirit of this invention as defined by the following claims.

I claim:

1. A basket ball backstop construction comprising a board carrying frame, an overhead support to which said frame is pivotally attached, bracing means extending rearwardly and upwardly from the lower end of said frame, said bracing means being pivotally attached at a fixed point to the lower end of said frame and pivotally connected at its upper end to an overhead support and comprising telescoping elements, said telescoping elements being arranged to compress the air between the same in one direction of relative movement between the elements.

2. A basket ball backstop construction comprising a board carrying frame, an overhead support to which said frame is pivotally attached, bracing means extending rearwardly and upwardly from the lower end of said frame, said bracing means being pivotally attached at a fixed point to the lower end of said frame and pivotally connected at its upper end to an overhead support and comprising telescoping elements, said telescoping elements being arranged to compress the air between the same in one direction of relative movement between the elements, and means for releasing the air from between said elements at a predetermined rate.

3. A basket ball backstop comprising a board supporting frame pivotally supported at its upper end to an overhead support, rear braces for said frame pivotally attached at a fixed point to the lower end of the frame and extending rearwardly and upwardly to an overhead support and having pivotal connections therewith, said rear braces each comprising telescoping members, a spring actuated latching element for each of said telescoping braces, and means for simultaneously releasing said latching elements.
